UNITED STATES PATENT OFFICE.

HECTOR RABEZZANA, OF FLINT, MICHIGAN, ASSIGNOR TO AC SPARK PLUG COMPANY, OF FLINT, MICHIGAN, A CORPORATION OF MICHIGAN.

PRESS FOR FORMING INSULATING MEMBERS FOR SPARK PLUGS.

Application filed May 8, 1922. Serial No. 559,307.

To all whom it may concern:

Be it known that I, HECTOR RABEZZANA, a subject of the King of Italy, and a resident of Flint, county of Genesee, and State 5 of Michigan, have invented certain new and useful Improvements in Presses for Forming Insulating Members for Spark Plugs, of which the following is a full, clear, concise, and exact description, such as will enable others skilled in the art to which the invention relates to make and use the same, reference being made therein to the accompanying drawings, which form a part of this specification.

15 My invention relates to extruding presses designed to form blanks for the insulating members of spark plugs from a plastic porcelain material composed for the most part of clay, by forcing the said material 20 from a cylinder through a suitable die or passage and dividing the issuing stream or column into proper lengths for insulator blanks; although my invention is capable of various other uses and is not limited to the 25 spark plug art as various parts and features thereof are capable of use in extruding presses generally, irrespective of the particular product or article produced in the operation thereof.

30 The principal object of my invention is to provide a device of the class above mentioned wherein the blanks produced will conform more closely to the form of the finished insulators than has heretofore commonly been the case, so that the amount of 35 material which has to be removed by turning, forming or equivalent shaping operation performed upon the blanks before drying and firing them, is reduced to a minimum; and a further object of my invention 40 is to provide various improvements in and relating to subordinate parts and auxiliary features of presses of the type above mentioned, and which are capable of use in most 45 cases in extruding presses generally, irrespective of the character of the product thereof.

With the above and other objects of invention in view my invention consists in the 50 improved extruding press and subordinate parts and elements thereof illustrated in the accompanying drawings and hereinafter described and claimed; and in such variations and modifications thereof, within the scope 55 of the concluding claims, as will be obvious

to those skilled in the art to which my invention relates.

In the drawings accompanying and forming a part of this specification and wherein the preferred embodiment of my invention 60 is illustrated:

Figure 1 is a view showing my improved press partly in side elevation and partly in section, the same being shortened by leaving out a considerable intermediate length 65 of the cylinder, and of various connecting rods and other elements of the device.

Figure 2 is a view showing a section upon horizontal planes indicated by the line 2, 2, Figure 1, looking down.

70 Figure 3 is a similar view upon a plane indicated by the line 3, 3, Figure 1.

Figure 4 is a fragmentary sectional view upon a vertical plane showing the passage or nozzle through which the plastic clay material is forced from the press, and various 75 elements associated therewith, upon a larger scale than in Figure 1.

Figure 5 is a view taken upon a horizontal plane indicated by the line 5, 5, Figure 4, looking up.

Figure 6 is a view showing certain other mechanism located adjacent the discharge nozzle and cooperating therewith.

Figure 7 is a view showing a section upon 85 a vertical transverse plane indicated by the line 7, 7, Figure 2, the screw operating member hereinafter referred to, however, being shown in its central position.

Figure 8 is a view showing the lower or 90 base portion of my improved press in elevation and from a position to the left of Figure 2.

Figure 9 is a view relating to the column 95 of plastic material issuing from the nozzle or outlet passage of the press in the operation thereof, and referred to hereinafter in explaining the operation of my invention.

Referring now to the drawings wherein 100 like parts are designated by the same reference numerals in the several views, the numeral 10 designates a suitable base casting, and 11, 11 two tension members or tie rods extending upwardly therefrom and which support a head 12 at their upper ends; and 105 13 designates a cylinder extending between the head and a platform 14 which is supported between and in fixed relation to the base 10 and head 12; the middle part of the cylinder being broken away to reduce the 110

length of the view in which it is shown, and the same forming a receptacle in which the plastic material is contained and from which it is forced when the machine is in operation, as will hereinafter appear. In practice the base is located beneath a floor, and the platform may be substantially at the level of the floor, or the base may rest upon a floor above which the platform is supported by suitable supporting members; as these are features not directly involved in my invention. The platform commonly extends to one side of the head and the normal position of the base of the cylinder so that a cylinder filled with clay may be placed thereupon, and then moved sidewise and into proper position beneath the head and relative to an outlet extending therethrough and relative to a piston arranged to enter the cylinder and move upward therein to thereby extrude the clay therefrom; and said cylinder is provided with a packing ring 15 at its upper end which is pressed into firm contact with the under side of the head upon initial upward movement of the piston as it enters the cylinder, and is so held during the time that the clay is being forced therefrom. The cylinder is made slightly shorter than the distance between the head 12 and platform 14 so that it may be moved sidewise on the platform and removed to refill it, and then returned to proper position in the press; and a plurality of readily removable pins 16 fit in holes in the platform to properly position the lower end of the cylinder, so that the piston may enter therewith, in the embodiment of my invention illustrated.

The piston above referred to is designated by the reference numeral 17 and is shown as supported upon the upper end of a sleeve 18 carried by the reciprocating cross head 19 which is guided by the tension rods 11, or otherwise, the middle portion of the sleeve being broken away as the length thereof corresponds approximately with the length of the cylinder, so that the piston may be moved throughout substantially the entire length of the cylinder; and up and down movement is imparted to the cross head and to the piston by a screw 20 cooperating with a nut 21, which is carried by the cross head, as shown. The parts are so constructed and arranged that the upper end of the piston may move downward slightly below the upper surface of the platform 14, so as to clear the lower end of the cylinder and permit it to be moved sidewise to remove an empty cylinder and replace the same by a filled one; and moved upward far enough to force all, or substantially all, of the clay contained within the cylinder out therefrom and through an outlet passage 22 leading from the cylinder through the head and to a point above the same. This outlet passage is shown as provided in and extending through

a tube or nozzle 23 which is made separate from the head 12 and is screwed into a threaded opening therein, in the particular embodiment of my invention illustrated and described herein.

The screw 20 is operated from a pulley 24 secured to a suitable shaft which operates a second shaft 25 through suitable gearing 26, 27, and which shaft 25 carries a grooved arm 28 along which a crank pin 29 is adjustable as by a screw 30; and which crank pin is connected with a reciprocating member 31 slidable in a suitable guide secured to the base 10 through a pitman 32, the ends of which are secured one to said crank pin and the other to said reciprocating slide member. The sliding member 31 is operatively connected with an arm 33 extending from an oscillating screw actuating member 34 which is loose upon the screw 20, and which arm is slidable in a transverse hole provided in a cylindrical rocking member 35 supported in a bearing in said sliding member; and said oscillating member carries a plurality of spring pressed pawls, one of which is shown at 36, and which pawls engage a ratchet wheel 37 which is secured to the screw 20 so as to drive the same; whereby reciprocating movement of the slide 31 will impart oscillatory movement to the member 34, and intermittent or step by step rotary movement to the screw 20.

The arrangement of the parts thus far referred to is such that movement of the screw 20 as aforesaid forces the piston 17 upward, and forces the plastic clay material out from the cylinder 13 through the passage in the nozzle 23, as will be appreciated. The gear 27 is rotatable independently of the shaft 25 and is connected therewith to drive the same through any suitable clutch mechanism shown, conventionally, as a sliding jaw clutch 38; so that the machine may be stopped at any time preferably through a foot operated pedal 39 upon the platform 14 near where the operator is supposed to stand, and which pedal is operatively connected with the clutch through any suitable connecting members. When all or nearly all the porcelain or clay material has been forced from the cylinder 13 the machine will be stopped, the pawls 36 withdrawn and held away from the ratchet 37, and the screw 20 rotated reversely through a hand operated pinion 40 meshing with a gear 41 fast upon the said screw until the piston 17 is moved below the upper surface of the platform 14, whereupon the empty cylinder may be moved laterally and refilled with clay material; or removed entirely from the press and a second filled cylinder substituted therefor, as hereinbefore explained.

The reference numeral 42 designates a reciprocating sleeve surrounding and movable

vertically upon and relative to the nozzle 23 and having an inwardly extending flange 43 at its upper end, and an outwardly extending flange 44 at its lower end, 5 and which sleeve is forced and held upwardly by a spring 45 acting between the upper end of the head 12 and the under side of the said flange 44; said sleeve being pulled downwardly by a yoked lever 46 pivotally supported at 47 and the two sides of which, 10 see Figure 3, are bent downward (as shown in Figure 1) and bear upon the flange 44 at diametrically opposite points. This lever 46 is operated by a rod 471 the upper end 15 of which is pivotally connected therewith at 48, and the lower end of which is pivotally connected at 49 with a connecting member 50 in threaded engagement with a passage provided in an oscillating sleeve 51 20 pivotally supported at 52; and which sleeve is operated from a cam 53 which is fast upon the shaft 25 and which acts upon a roller 54 at the free end of a carrier 55 similar to the member 50, and similarly 25 adjustable to vary the effective length of the lever formed by the sleeve 51 and the members 50 and 55; the features of adjustment being provided to regulate closely the downward movement imparted to the sleeve 42 30 and to maintain uniformity as regards the effect produced by such downward movement upon the column of plastic material issuing from the passage 22 when the press is in operation.

35 Located between the upper end of the discharge nozzle 23 and the flange 43 of the sleeve 42 is an annular compressible member 56 made, for example, of rubber and which, while normally of an internal diameter corresponding approximately with the passage 22 will, upon being compressed by downward movement of the sleeve 42, assume the form indicated in dotted lines in Figure 4 and act to reduce the area of 40 the passage through the said nozzle; or, as otherwise expressed, will act to constrict the passage through which the plastic material flows from the press when the inner periphery of said annular member is moved inward, radially, and toward the axis of said 45 passage; such movement occurring periodically and once during each rotation of the shaft 25, as will be appreciated. The effect of this is to reduce the diameter of the stream or column of plastic material issuing from the passage 22 (and which would otherwise be cylindrical) at regular intervals along the length thereof, as shown at 50 a, b and c in Figure 9; thus producing a series of blanks conforming closely to the finished form of the insulators and economizing in the use of clay material; as these reduced portions constitute the end portions of the blanks from which the insulating 55 members are formed, which end portions are

of material less diameter than the intermediate portion *d* of the insulator which is held in place in the casing of the spark plug for which the finished insulating members are provided. 70

The extent of reduction in diameter of the issuing column of plastic material at intervals along the same, as well also as the form of such reduced portions, are obviously dependent upon the form of the cam 53 and upon the extent to which the inner wall of the annular constrictible member 56 is forced inward as hereinbefore explained; the degree of compression and consequent distortion of said member being 80 dependent upon the adjustment of the members 50 and 55 with a cam of definite throw, as will be understood. It will also be appreciated that the blanks are intended to be subjected to a subsequent turning operation in a machine resembling a lathe and wherein the blanks are given a form corresponding with the finished insulators; the reducing of the diameter of the issuing column of plastic material being for the purpose of economizing in material and producing blanks approximating the form of the finished insulators, and not to produce insulators in their precise finished form. 90

The issuing column of clay material is cut 95 transversely at the reduced portions thereof, that is, approximately at the points *e* in Figure 9, to thereby provide individual blanks from which the insulating members to be produced are formed; the cutting mechanism being adjustable so as to sever the column at different places along the reduced portions and between successive full sized portions (which are formed at such times as the annular constrictible member is not 105 compressed and distorted); to thereby vary the relative lengths of the reduced portions at the two ends of the blanks, as will be understood. 100

110 The severing of the issuing column of clay material into individual spark plug insulator blanks is accomplished by a knife 57 secured to the upper end of an oscillating shaft 58, see Figures 4 and 5, extending through a bearing passage in a pulley 59 115 which is shown as rotatable upon the sleeve 42, and which pulley is driven in any way as through a belt 60; said shaft having an arm 61 at its lower end acted upon by a spring 62 which serves to keep the knife out 120 of the path of the issuing column of plastic material and which arm carries a set screw 63 through which the arm 61 and shaft 58 are operated to swing the knife 57 inward at proper intervals to cut the column apart 125 at the proper points. The means illustrated for operating the knife 57 comprises a reciprocating annular conical cam 64 surrounding and movable vertically upon the sleeve 42 and the upper end of which, as 130

said cam is moved upward, engages the free inner end of the set screw 63 and swings the arm 61 outward, thus causing movement of the knife inward and toward the axis of the nozzle and across the column of clay issuing therethrough; the set screw being adjustable to limit outward swinging movement of the knife by a suitable nut thereupon, as best shown in Figure 5. This 10 cam is operated by a second bifurcated lever 65 also pivotally supported at 47, and the free inner ends of which are pivotally connected at 66 to opposite sides of the conical cam 64 so as to move the same both upward and downward; the outer end of this lever being pivotally connected at 67 with the upper end of a vertically movable operating rod 68. The lower end of this operating rod extends through an opening in a 20 guide 69 carried by the base of the machine, and is pushed upwardly by a spring 70 acting thereupon; said rod being moved downward by an oscillating frame 71 pivotally supported from the base at 72 and having a 25 hole through which the lower end of the rod extends, a nut being threaded upon said lower end to provide an abutment for communicating downward movement to the rod. The frame 71 is swung downward by a roller 30 at the lower end of a short link 73 pivotally connected with the free end of the slide 31, and which roller acts upon an inclined cam 74 upon the frame as the slide moves to the left, Figure 1; the lower end of the link being free to swing toward the left as the slide 35 returns toward the right, but prevented from movement in a reverse direction beyond a substantially vertical position by cooperating stops at the joint between said link and the slide.

Extending upward from the abutment 12 are two guide rods 75, 75 connected together at their upper ends by a cross bar 76; and 77 designates a reciprocating cross head 45 having guide tubes 78, 78 slidable upon the said guide rods, the extent of movement of said cross head being determined by abutments 79, 80 carried by rods 81, 81 supported from the cross bar 76, as best shown 50 in Figure 6 of the drawings. The cross head 77 carries a guide tube 82 within which a reciprocating blank piercing and supporting needle or spindle 83 operates, suitable manually operable latch mechanism 84 carried by the cross head being provided for holding the spindle in the lowermost position in which it is shown. A comparatively long spring 85 has its lower end connected with the upper end of the needle 83 and its 55 upper end connected to a fixed abutment, and said piercing member is provided with a cross handle 86 which the operator of the machine may grasp to force the needle downward; the spring 85 being made long 60 in order that its tension or lifting action

will not vary greatly whatever may be the position of the cross head and of the piercing needle relative thereto.

The operation of this last described part of my invention is substantially as follows: 70 Assuming a blank to have been cut off from the end of the advancing stream or column of plastic material issuing through the passage 22 and removed from the machine, the operator will now grasp the handle 86 and 75 depress the spindle 83, as well also as the cross head 77; the spindle being thus forced into the mass of plastic material at the outlet end of the discharge passage and forming the passage in the insulator blank 80 through which the inner insulated electrode of the finished plug extends. The spindle is shown as of two diameters in order that the passage thus provided may be of greater diameter at the top or outer end of the 85 blank than at the lower inner end, as the central electrodes of the type of the plug for which the insulators which the machine illustrated is intended to produce are larger 90 at their outer than at their inner ends. 90

The latch 84 will catch and hold the needle 83 in its lowermost position and as the column of plastic material issues from the nozzle, slowly, as will be appreciated, the needle and cross head will move upward 95 until a length corresponding with a blank shall have issued from the nozzle; the mechanism for reducing the cross-sectional area of the issuing stream having operated meanwhile, as will be understood. 100

After a blank has been forced from the nozzle and formed the cutting mechanism operates to sever it from the advancing column, leaving the blank impaled upon the spindle; after which the operator grasps the 105 blank and operates the latch 84, whereupon the spring 85 will withdraw the spindle from the blank so that it may be again depressed as hereinbefore explained.

Having thus described and explained my 110 invention, I claim and desire to secure by Letters Patent:

1. In a machine of the class described, a receptacle adapted to contain a plastic material; a passage leading from said receptacle; means for forcing plastic material out from said receptacle through said passage; and means associated with said passage for periodically constricting the same, to thereby reduce the area of the stream of plastic material issuing from said passage at intervals along the length thereof. 115

2. In a machine of the class described, a receptacle adapted to contain a plastic material; a passage leading from said receptacle; means for forcing plastic material out from said receptacle through said passage; and means for regularly and periodically varying the area of said passage as the 125 plastic material flows therethrough, to there- 130

- by vary the area of the stream of plastic material issuing from said passage at intervals along the length thereof.
3. In a machine of the class described, a receptacle adapted to contain a plastic material; a nozzle having a passage through which plastic material may flow from said receptacle; means for forcing plastic material out from said receptacle through said passage; an constrictible member associated with said nozzle and adapted to reduce the area of the passage aforesaid; and means constricting said member at regular intervals as plastic material flows from said receptacle through said passage.
4. In a machine of the class described, a receptacle adapted to contain a plastic material; a nozzle having a passage through which plastic material may flow from said receptacle; means for forcing plastic material out from said receptacle through said passage; an annular member carried by said nozzle and through which plastic material flowing through said passage flows; means carried by said nozzle for forcing the inner periphery or wall of said member inward toward the axis of said nozzle to thereby reduce the area of the passage aforesaid; and means for operating said forcing means at regular intervals as the plastic material flows from said receptacle.
5. In a machine of the class described, a receptacle adapted to contain a plastic material; a nozzle having a passage through which plastic material may flow from said receptacle; means for forcing plastic material out from said receptacle through said passage in a substantially continuous stream; and means carried by said nozzle and acting upon the stream of plastic material issuing therefrom for reducing the cross-sectional area of said stream at regular intervals.
6. In a machine of the class described, a receptacle adapted to contain a plastic material; a nozzle having a passage through which plastic material may flow from said receptacle; means for forcing plastic material out from said receptacle through said passage; an annular member carried by said nozzle and registering with the passage therein and which member is yieldable in the direction of its axis, and the arrangement of which is such that its inner periphery or wall moves inward radially and toward the axis of the passage aforesaid as said member is compressed; and means for compressing said yieldable member at regular intervals as a stream of plastic material issues from said nozzle.
7. In a machine of the class described, a receptacle adapted to contain a plastic material; a nozzle having a passage through which plastic material may flow from said
- receptacle; means for forcing plastic material out from said receptacle through said passage; an annular member carried by said nozzle and registering with the passage therein and which member is yieldable in the direction of its axis, and the arrangement of which is such that its inner periphery or wall moves inward radially and toward the axis of the passage aforesaid as said member is compressed; a reciprocating sleeve surrounding and movable upon said nozzle, and the upper end of which is in engagement with said annular member; and means for operating said sleeve at regular intervals to thereby compress said yieldable member as a stream of plastic material issues from said nozzle.
8. In a machine of the class described, a cylinder adapted to contain a plastic material; a nozzle having a passage through which plastic material may flow from said cylinder; a piston movable in said cylinder; a rotating shaft operatively connected with said piston; and means associated with said nozzle and operated from the shaft aforesaid for reducing the cross-sectional area of the stream of plastic material flowing through said passage at regular intervals along the length thereof.
9. In a machine of the class described, a cylinder adapted to contain a plastic material; a nozzle having a passage through which plastic material may flow from said cylinder; a piston movable in said cylinder; a rotating shaft operatively connected with said piston; an annular member carried by said nozzle and registering with the passage therein, and the periphery or wall of which is movable radially relatively to the axis of the passage in said nozzle; and means operated by said shaft for moving the inner periphery of said annular member inward as aforesaid at regular intervals as a stream of plastic material issues from said nozzle.
10. In a machine of the class described, a cylinder adapted to contain a plastic material; a nozzle having a passage through which plastic material may flow from said cylinder; a piston movable in said cylinder; a rotating shaft; a reciprocating slide operated by said shaft; ratchet mechanism operated by said slide and through which said piston is operated; an annular member carried by said nozzle and registering with the passage therein, and the inner periphery or wall of which is movable radially relatively to the axis of the passage in said nozzle; and means operated by said shaft for moving the inner periphery of said annular member inward as aforesaid at regular intervals as a stream of plastic material issues from said nozzle.
11. In a machine of the class described, a cylinder adapted to contain a plastic material; a nozzle having a passage through

which plastic material may flow from said cylinder; a piston movable in said cylinder; a rotating shaft; a reciprocating slide operated by said shaft; ratchet mechanism operated by said slide and through which said piston is operated; and means associated with said nozzle and operated from the shaft aforesaid for reducing the cross-sectional area of the stream of plastic material flowing through said passage at regular intervals along the length thereof.

12. In a machine of the class described, a cylinder adapted to contain a plastic material; a nozzle having a passage through which plastic material may flow from said cylinder; a piston movable in said cylinder; a rotating shaft operatively connected with said piston; an annular member carried by said nozzle and registering with the passage therein, and the inner periphery or wall of which is movable radially relatively to the passage in said nozzle; a reciprocating sleeve carried by said nozzle and which sleeve is operatively connected with said annular member; and means operated by said shaft for operating said sleeve to thereby move the inner periphery of said annular member inward as aforesaid at regular intervals as a stream of plastic material issues from said nozzle.

13. In a machine of the class described, a cylinder adapted to contain a plastic material; a nozzle having a passage through which plastic material may flow from said cylinder; a piston operating in said cylinder; a rotating shaft; a reciprocating slide operated by said shaft; ratchet mechanism operated by said slide through which said piston is operated; cutting mechanism carried by said nozzle and adapted to sever a stream of plastic material issuing therefrom at regular intervals; and means operated by said reciprocating slide for intermittently operating said cutting mechanism.

14. In a machine of the class described, a cylinder adapted to contain a plastic material; a nozzle having a passage through which plastic material may flow from said cylinder; a piston operating in said cylinder; a rotating shaft operatively connected with said piston; a rotating pulley carried by said nozzle; a swinging knife carried by said pulley and movable toward and from the axis of said nozzle; and means operated by said shaft for intermittently moving said knife toward the axis of said nozzle to thereby sever the stream of plastic material issuing therefrom at regular intervals.

15. In a machine of the class described, a cylinder adapted to contain a plastic material, a nozzle having a passage through which plastic material may flow from said cylinder; a piston operating in said cylinder; a rotating shaft operatively connected with said piston; a rotating pulley carried

by said nozzle; an oscillating shaft carried by said rotating pulley, and the axis of which is parallel with the axis of said nozzle; a swinging knife carried by said shaft; an arm carried by said shaft; a reciprocating annular cam carried by said nozzle and adapted to engage the arm aforesaid to thereby swing said knife inward toward the axis of said nozzle; and means operated by said rotating shaft for operating said annular cam.

16. In a machine of the class described, a cylinder adapted to contain a plastic material; a nozzle having a passage through which plastic material may flow from said cylinder; a piston movable in said cylinder; a rotating shaft operatively connected with said piston; an annular member carried by said nozzle and registering with the passage therein, and the inner periphery or wall of which is movable radially relatively to the axis of the passage in said nozzle; a reciprocating sleeve carried by and movable upon said nozzle, and which sleeve is operatively connected with said annular member; a cam carried by said rotating shaft and which cam is operatively connected with said reciprocating sleeve; a rotating pulley carried by said reciprocating sleeve; a swinging knife carried by said pulley and movable toward and from the axis of said nozzle; and means operated by said shaft for intermittently moving said knife toward the axis of said nozzle.

17. In a machine of the class described, a cylinder adapted to contain a plastic material; a nozzle having a passage through which plastic material may flow from said cylinder; a piston movable in said cylinder; a rotating shaft; a reciprocating slide operated by said shaft; ratchet mechanism through which said piston is operated from said slide; an annular member carried by said nozzle and registering with the passage therein, and the inner periphery or wall of which is movable radially relative to the passage in said nozzle; a rotating pulley carried by said nozzle; an oscillating shaft carried by said pulley, and the axis of which is parallel with the axis of said nozzle; an arm carried by said oscillating shaft; a swinging knife carried by said oscillating shaft; a reciprocating cam carried by said nozzle; means whereby movement of said cam is communicated to said arm and to said oscillating shaft to thereby swing said knife inward toward the axis of said nozzle; and means whereby and through which said cam is operated from said reciprocating slide.

18. In a machine of the class described, a receptacle adapted to contain a plastic material; a passage leading from said receptacle; means for forcing plastic material out from said receptacle through said pas-

- sage; means acting upon the stream of plastic material as it issues from said passage for reducing the area of said stream at intervals along the length thereof; and cutting mechanism located adjacent said passage and adapted to sever the stream of plastic material issuing therefrom at regular intervals.
19. In a machine of the class described, a receptacle adapted to contain a plastic material; a passage leading from said receptacle; means for forcing plastic material out from said receptacle through said passage; means for regularly and periodically varying the area of said passage as the plastic material flows therethrough, to thereby vary the area of the stream of plastic material issuing from said passage at intervals along the length thereof; and cutting mechanism located adjacent said stream as it issues from said passage and adapted to sever said stream at regular intervals.
20. In a machine of the class described, a receptacle adapted to contain a plastic material; a nozzle having a passage through which plastic material may flow from said receptacle; means for forcing plastic material out from said receptacle through said passage; a constrictible member associated with said nozzle and adapted to reduce the area of the passage aforesaid; means for constricting said member at regular intervals as plastic material flows from said receptacle through said passage; and cutting mechanism carried by said nozzle and adapted to sever the stream of plastic material issuing therefrom at regular intervals.
21. In a machine of the class described, a receptacle adapted to contain a plastic material; a nozzle having a passage through which plastic material may flow from said receptacle; means for forcing plastic material out from said receptacle through said passage in a substantially continuous stream; means carried by said nozzle and acting upon the stream of plastic material issuing therefrom for reducing the cross-sectional area of said stream at regular intervals; and cutting mechanism carried by said nozzle and adapted to sever the stream of plastic material issuing therefrom at regular intervals.
22. In a machine of the class described; a fixed abutment; a nozzle carried by said abutment; a platform located below and spaced apart from said abutment; a cylinder adapted to contain a plastic material, and which cylinder extends between said platform and said abutment; a piston adapted to operate in said cylinder, and which piston is movable into a position below the upper surface of said platform; and means for operating said piston.
23. In a machine of the class described; a fixed abutment; a nozzle carried by said
- abutment; a platform spaced apart from said abutment; a cylinder adapted to contain a plastic material, and which cylinder extends between said platform and said abutment; a piston adapted to operate in said cylinder, and which piston is movable into a position below the lower end thereof; a rotating shaft, and ratchet mechanism through which said piston is operated from said shaft.
24. In a machine of the class described; a fixed abutment; a nozzle carried by said abutment; a platform located below and spaced apart from said abutment; a cylinder adapted to contain a plastic material, and which cylinder extends between said platform and said abutment; a piston adapted to operate in said cylinder, and which piston is movable into a position below the upper surface of said platform; a rotating shaft; a reciprocating slide operated by said shaft; a screw operatively connected with said piston; and ratchet mechanism through which said screw is operated intermittently from said reciprocating slide.
25. In a machine of the class described; a fixed abutment; a nozzle carried by said abutment; a platform located below and spaced apart from said abutment; a cylinder adapted to contain a plastic material, and which cylinder extends between said platform and said abutment; a piston adapted to operate in said cylinder, and which piston is movable into a position below the upper surface of said platform; a screw operatively connected with said piston and adapted to move the same in one direction; a rotating shaft; means whereby said screw is operated intermittently from said shaft; a gear carried by said screw; and a pinion operatively connected with said gear and adapted to operate said screw to thereby move said piston in a reverse direction.
26. In a machine of the class described, a receptacle adapted to contain a plastic material; a passage leading from said receptacle; means for forcing plastic material out from said receptacle through said passage; a reciprocating spindle disposed adjacent the outlet end of said passage and movable into the mass of plastic material issuing therefrom; and cutting mechanism located adjacent the outlet end of said passage and adapted to sever the stream of plastic material issuing therefrom at regular intervals.
27. In a machine of the class described, a receptacle adapted to contain a plastic material; a nozzle having a passage through which plastic material may flow from said receptacle; means for forcing plastic material out from said receptacle through said passage; a reciprocating spindle disposed adjacent the outlet end of said passage and movable in the direction of the axis of said passage into the mass of plastic material.

contained therein; and cutting mechanism located adjacent the discharge end of said nozzle and adapted to sever the stream of plastic material issuing therefrom at regular intervals.

28. In a machine of the class described, a cylinder adapted to contain a plastic material; a head or abutment at the upper end of said cylinder; a nozzle carried by said abutment and having a passage extending therethrough; means for forcing plastic material out through said nozzle; guide members carried by said abutment and extending substantially parallel with the axis of said nozzle; a reciprocating spindle movable in the direction of the axis of said nozzle and into the mass of plastic material issuing therefrom, and which spindle is guided in its movement by said guides; and cutting mechanism located adjacent the outlet end of said nozzle and adapted to sever the stream of plastic material issuing therefrom at regular intervals.

29. In a machine of the class described, a cylinder adapted to contain a plastic material; a head or abutment at the upper end of said cylinder; a nozzle carried by said abutment and having a passage extending therethrough; means for forcing plastic material out through said nozzle; guide members carried by said abutment and extending substantially parallel with the axis of said nozzle; a cross-head movable upon and guided by said guides; a reciprocating spindle carried by said cross-head and movable in a direction parallel with the axis of said nozzle and into the mass of plastic material contained therein; and cutting mechanism located adjacent the outlet end of said passage and adapted to sever the stream of plastic material issuing therefrom at regular intervals.

30. In a machine of the class described, a cylinder adapted to contain a plastic material; a head or abutment at the upper end of said cylinder; a nozzle carried by said abutment and having a passage extending therethrough; means for forcing plastic material out through said nozzle; guide members carried by said abutment and extending substantially parallel with the axis of said nozzle; a cross-head movable upon and guided by said guides; a guide tube carried by said cross-head; a spindle movable in said guide tube and in a direction parallel with the axis of said nozzle and into the mass of plastic material issuing therefrom; a latch for retaining said spindle in a lowermost position; a spring operatively connected with said spindle and adapted to move the same when released from the holding action of said latch; and cutting mechanism located adjacent the outlet end of said passage and adapted to sever the stream of

plastic material issuing therewith at regular intervals.

31. In a machine of the class described, a cylinder adapted to contain a plastic material; a head or abutment at the upper end of said cylinder; a nozzle carried by said abutment and having a passage extending therethrough; means for forcing plastic material out through said nozzle; guide members carried by said abutment and extending substantially parallel with the axis of said nozzle; a cross-head movable relative to and guided in its movement by said guides; a guide tube carried by said cross-head; stops supported by said guide members and adapted to limit the extent of movement of said cross-heads; a reciprocating spindle operating in said guide tube and movable parallel with the axis of said nozzle and into the mass of plastic material issuing therefrom; latch mechanism carried by said cross-head and adapted to engage and retain said reciprocating spindle in its lowermost position; and a spring operatively connected with the upper end of said spindle and adapted to move the same upward when said spindle is relieved from the holding action of said latch mechanism.

32. In a machine of the class described, a cylinder adapted to contain a plastic material; a nozzle having a passage through which plastic material may flow from said cylinder; a piston movable in said cylinder; a rotating shaft; means operated from said shaft for forcing said piston into said cylinder to thereby cause plastic material to flow therefrom through said nozzle; an annular member carried by said nozzle and registering with the passage therein, and the periphery or wall of which is movable radially relatively to the axis of said nozzle; an annular member carried by said nozzle and registering with the passage therein, and which member is yieldable in the direction of its axis, and the arrangement of which is such that its inner periphery or wall moves inward radially and toward the axis of the passage aforesaid as said member is compressed; a reciprocating sleeve surrounding and movable upon said nozzle, and the upper end of which is in engagement with said annular member; a cam carried by said shaft; an oscillating lever operated by said cam; a pivotally supported lever operatively connected with the sleeve aforesaid; and a link intermediate the free end of said pivotally supported lever and said oscillating lever.

33. In a machine of the class described, a cylinder adapted to contain a plastic material; a nozzle having a passage through which plastic material may flow from said cylinder; a piston movable in said cylinder; a rotating shaft; means operated from said

shaft for forcing said piston into said cylinder to thereby cause plastic material to flow therefrom through said nozzle; an annular member carried by said nozzle and registering with the passage therein, and the periphery or wall of which is movable radially relatively to the axis of said nozzle; an annular member carried by said nozzle and registering with the passage therein, and which member is yieldable in the direction of its axis, and the arrangement of which is such that its inner periphery or wall moves inward radially and toward the axis of the passage aforesaid as said member is compressed; a reciprocating sleeve surrounding and movable upon said nozzle, and the upper end of which is in engagement with said annular member; an oscillating sleeve; an adjustable member carried by said sleeve and with which said cam engages; a second member carried by said sleeve and adjustable relative thereto; a rod operated by said last mentioned member; and a pivotally supported lever with which said rod is operatively connected, and which last men-

34. In a machine of the class described, a cylinder adapted to contain a plastic material; a nozzle having a passage through which plastic material may flow from said cylinder; a piston movable in said cylinder; a rotating shaft; means operated from said shaft for forcing said piston into said cylinder; a lever operatively connected with said piston; a sleeve operatively connected with said lever; and a lever operatively connected, and which last mentioned lever is operatively connected with said sleeve. 55

In testimony whereof I affix my signature.

HECTOR RABEZZANA.
